(57) **CLAIM**

I claim the ornamental design for a memo book organizer, as shown and described.

DESCRIPTION

FIG. 1 is a front elevation view of a memo book organizer, showing my new design;

FIG. 2 is a rear elevation view thereof;

FIG. 3 is a left side elevation view thereof;

FIG. 4 is a top plan view thereof;

FIG. 5 is a bottom plan view thereof; and,

FIG. 6 is a right front perspective view thereof.

The stipple and zig-zag patterned surfaces show typical hook and loop closure material.
